[57] CLAIM

The ornamental design for a golf bag cart, as shown and described.

DESCRIPTION

FIG. 1 is a perspective view of a golf bag cart showing my new design with the expansion links shown in FIGS. 2 and 3 omitted so the cart is adapted to receive small golf bags;

FIG. 2 is an enlarged top plan view thereof with the addition of expansion links in each of the U-shaped supports for receiving large golf bags; and

FIG. 3 is a sectional elevational view taken along line 3—3 in FIG. 2.
